UNITED STATES PATENT OFFICE.

JOHN S. DEAN, OF EDGEWOOD PARK, PENNSYLVANIA, ASSIGNEE TO WESTINGHOUSE ELECTRIC & MANUFACTURING COMPANY, A CORPORATION OF PENNSYLVANIA.

BRUSH HOLDER AND METHOD OF MAKING THE SAME.

Application filed November 2, 1920. Serial No. 421,818.

To all whom it may concern:

Be it known that I, JOHN S. DEAN, a citizen of the United States, and a resident of Edgewood Park, in the county of Allegheny and State of Pennsylvania, have invented a new and useful Improvement in Brush Holders and Methods of Making the Same, of which the following is a specification.

10 My invention relates to brushholders and it has particular relation to sheet metal brushholders and to the method of making the same.

One of the objects of my invention is to 15 provide a strong and rugged brushholder of relatively light weight and one that may be quickly and easily manufactured and assembled with a minimum of labor and expense.

20 Another object of my invention is to provide a brushholder having a brushbox of such construction as to protect the carbon brush carried thereby from foreign matter.

25 Heretofore, it has been customary to construct a brushholder from an integral casting of the desired general form which was afterwards machined or otherwise finished. A brushholder of this type was 30 not only relatively heavy but was also an expensive article to manufacture. Moreover, it has been observed that the carbon brushes employed in the brushholders of the above type became scarred and pitted

35 along the sides thereof, which not only affected the electrical contact but prematurely shortened the service of the brush.

It has not been definitely known heretofore, what caused this scarring of the sides 40 of the brush, whether it was occasioned by some unknown electrical phenomena or by dirt and grit working down between the sides of the brush and the brushbox.

45 Various experiments were, therefore, undertaken along these lines in order to determine the exact cause of this uneven wear. As a consequence thereto, it has been ascertained that, in the brushholders heretofore employed, the carbon brush extended 50 above the edge of the brushbox a distance sufficient to permit gritty particles to accumulate in the pocket formed by the top edge of the front wall of the brushbox and the side of the brush. Also, it has been 55 observed, that the front walls of the brush-

boxes are generally cut away to permit the vertical movement of the brush finger. This construction also forms a pocket within which foreign matter accumulates. By reason of the vertical reciprocations of the 60 brush within the brushbox, these particles of foreign matter gradually worked into the relatively soft surface of the brush and downwardly along the brush and between the surface of the same and the wall of 65 the brushbox, thereby causing vertical furrows and depressions to be formed in the side of the brush.

Briefly stated, my invention consists in 70 providing a brushholder, the various parts of which are formed from sheet metal blanks which are stamped, pressed or otherwise suitably bent into the desired form and which are thereafter secured together in the desired positions.

75 My invention further consists in so extending the continuous forward end of the brushholder, which constitutes the front wall of the brushbox, upwardly above the top of the brush as to overhang and prevent foreign matter from gaining access between the walls of the brush and the brushbox. A relatively low rear wall of the brushbox allows the brush finger ample space for vertical movement. The brush 80 finger may be so shortened or curved rearwardly as not to engage the continuous front wall of the brushbox.

In the accompanying drawings:

Figure 1 is a side elevation of a sheet 90 metal brushholder constructed in accordance with my invention.

Fig. 2 is a plan view of the structure illustrated in Fig. 1.

Fig. 3 is a rear view of the structure 95 illustrated in Figs. 1 and 2.

Fig. 4 is a plan view, on a reduced scale, of a sheet metal blank cut in the desired form and which, when bent, constitutes the front wall of the brushholder and the forward portions of the side walls.

100 Fig. 5 is a plan view, on a reduced scale, of a sheet metal blank of such shape that, when bent, it will constitute the rear end wall and the rear portions of the side walls 105 of the brushholder.

Fig. 6 is a plan view, on a reduced scale, of a sheet metal blank so cut that, when bent, it will constitute the rear wall of the brushbox and a re-inforcing member or 110

strap adjacent to the bottom of the brushholder.

Fig. 7 is a plan view on a reduced scale of a sheet metal blank so cut that, when bent, it will constitute a transverse reinforcing element.

Referring to the drawings.

The frame of the brushholder, preferably comprises a front element 1 and a rear element 2. The front element 1 is formed from a sheet metal blank 3, cut to the desired shape. (Fig. 4.) The blank 3 is bent along the dotted lines 4 to form substantially parallel side walls 5 connected by a continuous front end wall 6. The ends of the blank 3 are provided with outwardly projecting tongues, indicated as a whole at 7, and with inwardly extending slits 8 adjacent to the bottom edges of the tongues 7 which form lower tongue members 9. The tongues 7 are bent outwardly along the dotted lines 10 to form ears 11, and rearwardly and parallel to the sides 5, along the dotted lines 12 to form flanges 13. (Fig. 2.)

The rear element 2, of the brushholder frame, is formed in a manner substantially similar to the front element 1. A blank 14 (Fig. 5) is bent along the dotted lines 15 to form substantially parallel forwardly extending side walls 16 connected by a rear wall 17. The ends of the blank 14 are provided with outwardly projecting tongues, indicated as a whole at 18, and inwardly extending slits 19 adjacent to the bottom edges of the tongues 18 which form tongues 20. The tongues 18 are bent outwardly, in opposite directions from each other along the dotted lines 21, to form ears 22 and rearwardly along the dotted lines 23 and parallel to the side walls 16 to form flanges 24 (Fig. 2). The lower portion of the rear wall 17 is bent outwardly along the dotted line 25 to form a rearwardly extending flange 26 to which the rear end of a brush spring, not shown, may be secured.

The front and rear elements 1 and 2, thus formed, are assembled with the ears 11 and 22 in abutting and the tongues 9 and 20 in lapped relation, and are spot-welded or otherwise suitably secured together, as indicated at 27. The tongues 9 and 20 may be slightly offset to permit the walls 5 and 16 of the members 1 and 2 respectively to abut and to lie flush with each other.

A sheet metal blank 28 (Fig. 7) is suitably formed with a plurality of relatively wide end portions 29 connected by a relatively narrow portion or strap 30. The end portions 29 are cut, as indicated at 31 to form centrally disposed ears 32 and side portions 33. The ears 32 and the side portion 33 are bent upwardly along the dotted lines 34. The ears 32 are bent vertically upwards and the side portions 33 are bent upwardly and outwardly at an angle, as is

illustrated in Fig. 3 of the drawings. The end portions 29 are further bent along the dotted lines 35 to form flanges 36.

The member thus formed is disposed transversely with respect to the brushholder frame and adjacent to the juncture of the elements 1 and 2 (Fig. 2). The ears 32 are welded, as indicated at 37, to the overlapped tongues 9 and 20 of the elements 1 and 2 respectively, and at the same time securing the tongues together. The flanges 36 are welded to the tongues 13 and 24 respectively, as indicated at 38, thus securely tying together the side walls and effectively laterally bracing the structure.

A substantially T-shaped metal blank 39 (Fig. 6) is formed with a relatively wide portion 40 and a relatively long narrow portion 41 extending at right angles thereto. The portion 40 is bent vertically along the dotted line 42 and the extremities of the same are bent rearwardly along the dotted lines 43 to form substantially parallel ears 44. The end of the portion 41 is formed with an upwardly curved portion 45. (Fig. 1.)

The element thus formed is arranged in position with the portion 40 parallel to the front wall 6 of the brushholder and spaced therefrom, and it constitutes the rear wall of the brushbox. The ears 44 of the portion 40 are welded to the side walls 5, as at 46, and this arrangement additionally braces the structure against lateral stresses. The narrow portion 41 extends rearwardly and is welded to the strap 30 and to the rear wall 17 of the element 2, as indicated at 47 and 48 respectively.

The extensions formed by the abutting ears 11 and 22 and the flanges 13 and 24 respectively, are adapted to be engaged by the brushholder supporting posts 49, indicated by dotted lines in Fig. 1. The posts are provided at their lower extremities with diametrically extending slots 50 within which the abutting ears 11 and 22 are suitably secured.

By means of this construction, I obtain a brushholder that is relatively light in weight and rigid in construction, and one that may be manufactured at a minimum of labor and expense. Furthermore, it will be observed that, in a brushholder of this construction, the relatively high front wall 6 of the brushbox 51 will extend above the top of a brush 52 mounted therein and by reason of the usual angular disposition of the brushholder with respect to a commutator cylinder, the front wall will consequently overhang the brush and will prevent foreign matter from accumulating in pockets formed by the brush and the walls of the box. Also, by reason of the relatively low rear wall 40, foreign matter cannot collect on the top of the brush and similarly work down the rear

surface of the brush. The comparatively low rear wall of the brushbox permits the brush finger 53 to have ample vertical movement.

5 I claim as my invention:

1. A pressed steel brushholder comprising a plurality of separately formed main elements each of which is provided with a plurality of tongue members and a plurality of outwardly extending ear members, said elements being so arranged in end-to-end relation that the tongue and ear members of one element relatively overlap and abut the corresponding members of the other element.
- 10 2. A pressed steel brushholder comprising a plurality of separately formed elements each of which is provided with a plurality of tongue members and a plurality of outwardly extending ear members, said elements being so disposed in end-to-end relation that the tongue and ear members of one element respectively overlap and abut the corresponding members of the other element,
- 15 25 and a plurality of longitudinal and transverse reinforcing members secured to said elements.
3. The method of making a pressed steel brushholder which comprises, forming front and rear frame elements from sheet metal blanks, each of said elements being formed

with a plurality of corresponding tongue members and a plurality of laterally extending ear members, of forming a plurality of reinforcing members from sheet metal blanks, so disposing said elements in end-to-end relation that the corresponding tongue and ear members of each element respectively lap and abut each other, disposing the reinforcing members in position to brace said elements laterally and longitudinally, and welding the respective portions together.

4. A sheet-metal brushholder having a brushbox comprising a relatively high continuous front wall having integral backwardly bent extensions constituting side walls, a relatively low-cut rear wall having integral backwardly bent tabs secured to said side walls, and a supporting frame for the rear portions of said side-wall extensions.

5. A sheet-metal brushholder having a brushbox comprising a wall having integral bent extensions constituting side walls, a second wall having integral bent tabs secured to said side walls, and a supporting frame for the end portions of said side-wall extensions.

In testimony whereof, I have hereunto subscribed my name this 22nd day of October 1920.

JOHN S. DEAN.
